Primary Examiner — Ruth McInroy(74) *Attorney, Agent, or Firm* — Nelson Mullins Riley & Scarborough LLP(57) **CLAIM**

The ornamental design for a helmet with visor, as shown and described.

DESCRIPTION

FIG. 1 is a perspective view of a helmet with visor showing our new design;

FIG. 2 is a front view thereof;

FIG. 3 is a rear view thereof;

FIG. 4 is a left side view thereof;

FIG. 5 is a right side view thereof;

FIG. 6 is a bottom view thereof; and,

FIG. 7 is a top view thereof.

The broken lines of FIGS. 1-7 are illustrative of the visible environmental structure of the helmet with visor and form no part of the claimed design.
